UNITED STATES PATENT OFFICE.

ERNEST C. BARTH, OF PROVIDENCE, RHODE ISLAND.

STEAM-HEATER.

1,092,626.

Specification of Letters Patent.

Patented Apr. 7, 1914.

Application filed May 31, 1913. Serial No. 771,001.

To all whom it may concern:

Be it known that I, ERNEST C. BARTH, a citizen of the United States, residing at Providence, in the county of Providence and State of Rhode Island, have invented a new and useful Improvement in Steam-Heaters, of which the following is a specification.

This invention relates to certain new and useful improvements in steam heaters, and the objects thereof are to provide improved means for the instantaneous production of steam.

Further, the invention aims to provide a heater which has improved water containing sections that exhaust the heat from the sections and then cause same to act on the exteriors of the sections prior to its final exhaust from the heater.

Still further, the invention has for its object novel water holding sections of improved structure which derive maximum heat from the burners to effect the rapid formation of steam.

In the drawings: Figure 1 is a front elevation of the invention. Fig. 2 is a vertical transverse sectional view. Fig. 3 is a vertical longitudinal view. Fig. 4 is a section on the line 4—4 of Fig. 2. Fig. 5 is a section on the line 5—5 of Fig. 2, and Fig. 6 is a detail view in top plan of one of the burner manifolds.

The heater consists of a body 1 that has a horizontal gas supply pipe 2 connected thereto, the pipe 2 being common and connected to a series of depending pipes 3, each of which latter have a rotatable valve 4, the stems of which valves are provided with arms 5. The outer or free ends of the arms 5 are pivoted to a horizontal bar 6 which latter is common to all of the arms and serves to actuate the same in unison to thereby regulate the valves so as to increase or diminish the supply of gas. One end of the bar 6 is pivoted to one arm of a bell 45 crank lever 7 at 8, the lever 7 being pivotally supported at 9 from the body 1. The other arm of the lever 7 is connected to a chain or other flexible element 10 which latter passes over a wheel 11. The wheel 11 is 50 rigidly secured to a shaft 12 which latter is operated so as to be partially revolved by the customary diaphragm pressure regulator, not shown. A weight 13 acts as a counterbalance for the lever 7. An electric 55 lamp or bell 14 is included in an electrical circuit, which latter is closed to light the

lamp or sound the bell, by a contact 15 on the lever 7 which engages with a contact 16 that is included in said circuit, whereby should the regulator fail to work, the weight 13 will move down, thereby moving the contact 15 into engagement with the contact 16, closing the circuit through the lamp or bell and thus signaling to the operator the fact that the apparatus is working improperly.

Preferably there are three series of water coils 17, each series consisting of three coils the latter arranged longitudinally of the body shown in Fig. 3. A manifold, shown in Fig. 6, is used to supply gas to each of the three gas burners 18 of a series of water coils. Each manifold consists of a long outer pipe 19 that supplies gas to the rear-most burner, a short central pipe 20 that supplies gas to the front or forward burner, and a second outer pipe 21 of intermediate length that supplies gas to the intermediate or central burner. Each of the pipes 19, 20 and 21 are connected at their outer ends to the respective valves 4 by means of curved pipes 22.

The water and steam sections 23 are of substantially O-shape and completely surround the burners and coils, while the rear-most section in addition has a back vertical water space 24, the several sections being packed in the usual manner by soft copper gaskets and being held together by long tie bolts 25, which extend through openings 26 that are formed in the abutting faces of adjacent sections and register to form water passages, thus providing intercommunicating sections. The upper portion of each section 23 is formed with two series of vertical heat flues 27 the flues of each of which series communicate with common horizontal flues 28 that in turn are connected to a series of lateral horizontal flues 29. Flues 27 overlie the water coils, and the outer ends of the flues 29 extend through the outer sides of the sections 23 whereby the heat after passing through said flues 29, enters the space between the outer sides of the sections and the body 1 and escapes through the discharge flue 30. The flues 29, as depicted in Fig. 3 of the drawings, are formed by and between the abutting portions of adjacent sections. The upper ends of the water coils 17 are secured to the upper portions of the sections at 31, the lower ends of the coils being secured to the lower portions of the sections at 32, the steam being dis-

charged from the pipes 33 which may be of any desired number, and the condensed water is returned to the sections by the pipe 34. The sections are supplied with water by means of the pipe 35 which is connected to one of the sections by means of the boss 36 formed thereon. The sections 23 are formed with horizontal openings 23' which register and provide chambers in which the manifolds are received, vertical openings 24' being formed in the sections to receive the pipes 25' that support the burners 24. The pipe 37 enters through a suitable opening in the back of the last section, forms a loop in the heating chamber, then passes out through another opening in the back, the loop being supported by a hanger 38 shown in Fig. 3. This pipe is used as a hot water supply for general family use.

A steam gage 39, safety valve 40 and the usual water glass 41 are connected to the apparatus.

Having thus described my invention, I claim as new and desire to secure by Letters Patent:—

1. In a heater of the type set forth, an outer body, a series of substantially O-shaped hollow water containing sections arranged in the body and in abutting relation and having registering openings at their abutting portions, the rearmost of said sections having a vertical water space, the lower portions of the sections being formed with a series of horizontal registering openings that conjointly form a series of chambers, a series of water coils located in the centers of the spaces of the sections, said coils being connected at their upper and lower ends to the respective sections, a gas manifold in each of said chambers, said sections also having vertical openings that lead from said chambers to the said spaces of the sections, pipes connected to the manifolds and extending up through said last named vertical openings, burners on said pipes underlying the water coils, said sections having their upper portions formed with series of vertical flues and also formed with horizontal flues common to all of the vertical flues of a series thereof and further formed at their abutting portions with horizontal flues that lead from the common flues through the outer sides of the sections.

55 2. In a heater of the type set forth, an outer body, a series of substantially O-shaped hollow water containing sections arranged in the body and in abutting relation and having registering openings at their abutting portions, the rearmost of said sections having a vertical water space, a water coil connected to the upper and lower portions of each section and arranged in the central spaces of the sections, and a burner 60 for each coil underlying the same.

3. In a heater of the type set forth, an outer body, a series of substantially O-shaped hollow water containing sections arranged in the body and in abutting relation and having registering openings at their abutting portions, the rearmost of said sections having a vertical water space, the lower portions of the sections being formed with a series of horizontal registering openings that conjointly form a series of chambers, a series of water coils located in the centers of the spaces of the sections, said coils being connected at their upper and lower ends to the respective sections, a gas manifold in each of said chambers, said sections also having vertical openings that lead from said chambers to the said spaces of the sections, pipes connected to the manifolds and extending up through said last named vertical openings, and burners on said pipes 85 underlying the water coils.

4. In a heater of the type set forth, an outer body, a series of substantially O-shaped hollow water containing sections arranged in the body and in abutting relation and having registering openings at their abutting portions, the rearmost of said sections having a vertical water space, a water coil connected to the upper and lower portions of each section and arranged in the central spaces of the sections, and a burner for each coil underlying the same, said sections being formed with flues that lead from their said central spaces through the outer sides thereof to conduct the heat to the exteriors of the sections.

5. In a heater of the type set forth, an outer body, a series of substantially O-shaped hollow water containing sections arranged in the body and in abutting relation and having registering openings at their abutting portions, a series of water coils located in the centers of the spaces of the sections, said coils being connected at their upper and lower ends to the respective sections, burners underlying the water coils, said sections having their upper portions formed with vertical flues and also formed with a horizontal flue common to all of the vertical flues and further formed at their abutting portions with horizontal flues that lead from the common flue through the outer sides of the sections.

6. In a heater of the type set forth, a series of connected substantially O-shaped sections, each section having a manifold chamber at its lower portion, a manifold in each chamber, means to supply gas to the manifolds, and burners connected to each manifold.

7. In a heater of the type set forth, a series of connected substantially O-shaped abutting sections, each section being formed with a vertical flue that leads down into the space of the sections, adjacent sections being 130

formed at their abutting portions with horizontal flues that lead through the outer sides of the sections, said sections being further formed with a common flue that communicates with said vertical and horizontal flues, water coils in said space defined by the sections, and burners underlying the water coils.

8. In a heater of the type set forth, a series of connected water containing sections having hollow centers, water coils in said hollow centers connected to the sections, said sections having manifold chambers, manifolds in the chambers having pipes that extend therefrom into said hollow centers, and a burner underlying each coil and connected to said pipes.

9. In a heater of the type set forth, a series of water containing sections, each having a manifold chamber at its lower portion, the manifold chambers communicating with each other, a manifold having independent passages for supplying liquid fuel to the respective sections, and a burner for each manifold in connection with the respective passages.

10. In a heater of the type set forth, water containing means having a hollow center and formed with a vertical passage that leads down into said hollow center and further formed with a lateral passage located below the top of said means and which at one end communicates with said vertical passage and at its opposite end extends through said means, a water coil in said hollow center connected to the upper and lower portions of said means, and heating means in said hollow center, the heat after contacting with the coil entering the vertical passage and egressing through the lateral passage so as to act on the exterior of the water containing means.

11. In a heater of the type set forth, a water containing means having a hollow center and formed with a pair of spaced passages which lead down into said hollow central space and further with a pair of pas-

sages located below the top of said means and which lead from the respective first named passages through the opposite sides of said means, a water coil in said hollow center connected to the upper and lower portions of said means, and means in said hollow center to heat the coil, the heat after contacting with said coil entering the aforementioned passages and egressing therefrom acting on the exterior of the water containing means.

12. In a heater of the type set forth, a series of abutting water containing sections having hollow centers, water coils in said hollow centers connected to the upper and lower portions of the sections, said sections having flues formed between their abutting portions, which flues extend through one side of the sections, the sections being further formed with flues which extend from the hollow centers thereof into the first mentioned flues, and heating means for the coils, the heat after contact with the coils entering all of the aforementioned flues and egressing therefrom acting on the exteriors of the sections.

13. In a heater of the type set forth, a series of abutting water containing sections having hollow centers, said sections having longitudinal passages which register at the abutting points of the sections and coöperate to form a single longitudinal passage and each section also having a vertical passage which extends up into said longitudinal passage, the abutting sides of said sections being formed with lateral passages which extend from said longitudinal passage through the outer sides of said sections, and heating means in the hollow centers of the sections.

In testimony whereof I have signed my name to this specification in the presence of two subscribing witnesses.
